BULB GUIDE ON MOLDING DIAPHRAGM

John C. Whitesell, Chicago, Ill., assignor to Crane Co., Chicago, Ill., a corporation of Illinois

Application August 29, 1955, Serial No. 531,203

14 Claims. (Cl. 22—38)

The present invention relates to means for providing a recess in a mold during compaction thereof by diaphragm apparatus, and more particularly to a construction by which a bulb provided on a pressure-applying diaphragm in mold-forming apparatus to form a recess in the mold is accurately positioned at a desired location.

One type of apparatus for making molds for castings utilizes an elastic or expandable diaphragm to apply to the sand or other mold material the pressure necessary to provide a firm mold accurately reproducing the pattern. The present invention provides an improvement in such apparatus by which a recess may be formed in the mold, as, for example, to serve as an enlargement or reservoir at the mouth of the sprue or riser, substantially exactly at a predetermined location. To this end, a bulb or projection is formed on the diaphragm to press into the mold material as the diaphragm is expanded and thus form a reservoir or recess, and guide means are provided to assure that the bulb moves into the desired position.

It is accordingly an object of the present invention to provide, in mold-forming apparatus employing a pressure diaphragm means for forming a recess in the mold at a predetermined location.

It is another object of the invention to provide a reservoir-forming bulb on an expandable pressure-applying diaphragm of mold-forming apparatus and means for controlling the location of the bulb relative to passage-forming means in the mold.

Another object is the provision, in mold-forming apparatus of the type employing a diaphragm to apply pressure to moldable material, of guide means for accurately locating a projection provided on the diaphragm to form a recess in the mold material in a desired position.

A further object is the provision of a diaphragm construction presenting a bulb or projection on one face of a diaphragm and a guide rod fixed relative to the bulb and extending oppositely relative thereto.

The above and other objects, advantages, and features of the invention will be apparent from the following detailed description, taken in conjunction with the accompanying drawing, in which:

The single figure is a vertical sectional view through mold-forming apparatus incorporating one embodiment of the invention.

Referring to the drawing, there is shown a mold box 10, comprising part of a flask, such as a cope or drag, disposed on a pattern plate 11 on which a desired pattern 12 is mounted. A sprue form 13 extends from adjacent the pattern into the mold material 14, which in this case is shown as the usual molding sand. The form 13 is tubular and removably positioned at any appropriate point relative to the pattern. A form to provide a riser in the mold may also be employed, but in the present case a riser is dispensed with.

Means for compressing the sand or other molding material 14 are provided in the form of a pressure head 15 which comprises a casing 16 peripherally conforming to

2

the shape of the mold box and having a flange at its lower end, with a closure 16 extending between the walls thereof formed by a plate or plates suitably secured in place, as by welding. A diaphragm 17 of rubber or like material, or otherwise adapted to be expandable, is clamped peripherally in fluid-tight relation to the casing flange by a ring member 18 bolted to the flange and normally extends substantially horizontally. A fluid-tight pressure chamber 19 is thus defined by the head and diaphragm, into which fluid under pressure may be admitted through a conduit 20 under control of valve 21. When fluid under pressure enters the chamber, the diaphragm 17 passes upon the mold material 14 to compact the same about the pattern. Upon release of the pressure, the diaphragm returns to its normal substantially flat position. Suction means may be employed for retracting the diaphragm if desired. Any suitable means (not shown) may be utilized to hold the ring member and the top of the mold box tightly engaged during the application of the mold forming pressure.

In order to form a reservoir at the mouth of the sprue in the completed mold, a projection or bulb 22 of the desired shape is formed on the diaphragm extending exteriorly of the pressure chamber 19. The bulb is of substantially rigid construction, so that it may penetrate the mold material without difficulty. In the illustrated embodiment, the bulb is generally frusto-conical and comprises a solid metallic body or filler 23 having bonded to its outer surface a covering 24 of material similar to that of the diaphragm 17. An aperture is formed in the diaphragm through which the bulb projects, the covering 24 of the bulb being vulcanized or otherwise suitably secured to the diaphragm adjacent the aperture. The bulb 22 is so located on the diaphragm as to align with the sprue form 13. A guide rod 25 or similar rigid member extending interiorly of the pressure chamber 19 is fixed to the bulb for movement therewith, as by the threaded connection shown rigidly securing the rod to the bulb or by a pivotal or like connection permitting relative swinging of the bulb and rod. Means of any suitable type are provided in the chamber for receiving and guiding the rod, in the present instance taking the form of a tube 26 opening from the closure 16 and extending outwardly from the pressure chamber and thus forming a part thereof. The outer end of the tube is sealingly closed by a cap 27 so as to prevent escape of the pressure fluid from the chamber 19. The guide tube 26 is disposed substantially in alignment with the sprue form 13, and is so dimensioned relative to the rod 25 as to receive the latter for guided reciprocal movement therewith substantially in alignment with the sprue form. A certain amount of lateral movement of the rod is preferably provided for, however, as exaggeratedly shown in the drawing. The rod and tube in the disclosed embodiment are straight, but it is to be understood that if desired they may be curved so as to correspond to a curved path which the bulb is to follow in moving with the diaphragm.

It will be evident that when the diaphragm is expanded to compact the mold material, the bulb 22 is moved therewith until it comes into contact with the end of the sprue form by which its movement is halted, the guide means assuring that the bulb does not come to a position out of alignment with the sprue form. The bulb in its movement toward the sprue form displaces the sand or other mold material 14 out of its path, some of which is displaced downwardly through the form, so that no such material lies between the bulb and the mouth of the form. Thus, the sprue form and bulb together provide in the completed mold a sprue with an enlarged reservoir at its mouth in full communication therewith.

Upon completion of the pressure applying operation,

the diaphragm is retracted either by its own elasticity or by suction, as previously described, or in any other suitable manner. Obviously, the bulb may be employed to form a recess in the mold for other purposes than to provide a reservoir in communication with the sprue, and in such case the construction described assures that such recess will be properly located in every instance. If desired, suitable stop means may be provided to limit the movement of the rod 25, as to locate the bulb when it is not stopped by a form or other member disposed in the mold, or to prevent the possibility of excessive pressure of the bulb against the sprue form.

I claim:

1. In apparatus for making molds, a pressure head, an expandible pressure-applying diaphragm secured in sealed relation to said head and defining therewith a fluid-tight chamber, a substantially straight guide tube extending exteriorly of said chamber from the head closed at its outer end, a guide rod extending in the chamber reciprocably received in said tube, a substantially rigid bulb formed on the diaphragm exteriorly of the chamber in substantial alignment with said tube, and means fixing said rod to the bulb.

2. In apparatus for making molds, a pressure head, an expandible pressure-applying diaphragm defining a fluid-tight chamber with said head, a closed tubular projection on said head extending outwardly of said chamber and open to the chamber at its inner end, a substantially rigid bulb on said diaphragm exteriorly of the chamber, and a guide rod fixed to said bulb extending interiorly of the chamber reciprocably guided in said tubular projection.

3. In apparatus for forming molds, a pressure head, an expandible pressure-applying diaphragm defining a fluid-tight chamber with said head, a substantially straight tubular formation on said head open to the chamber at its inner end and closed at its outer end, a rod extending interiorly of the chamber reciprocably guided in said tubular formation, a substantially rigid projection on the diaphragm exteriorly of the chamber in substantial alignment with said tubular formation, and means fixing the projection to said rod.

4. In apparatus for making molds, a pressure head, an expandible pressure-applying diaphragm defining a fluid-tight chamber with said head, a substantially rigid projection on the diaphragm exteriorly of the chamber, a guide member extending interiorly of the chamber from said projection, and guide means on said head having an axis in substantial alignment with said projection receiving said member for reciprocating movement.

5. In apparatus for forming molds, a pressure head, an expandible pressure-applying diaphragm defining a fluid-tight chamber with said head, guide means fixed in said chamber having an axis passing through the chamber, a projection on the diaphragm exteriorly of the chamber substantially in alignment with said axis, and a member extending interiorly of the chamber secured to said projection and reciprocable in said guide means.

6. In apparatus for making molds, a pressure head, an expandible pressure-applying diaphragm defining a fluid-tight chamber with said head, fixed guide means in the chamber, means reciprocably guided in said guide means, and a bulb on said diaphragm exteriorly of the chamber fixed to said guided means, and movable by the diaphragm in a path determined by the aforesaid means.

7. In apparatus for making molds, a pressure head, an expandible pressure-applying diaphragm defining a fluid-tight chamber with said head, a bulb on said diaphragm exteriorly of the chamber and movable therewith, and means guiding movement of the bulb including guide means fixed in the chamber and means secured to the bulb for movement therewith guidedly engaging with said guide means.

8. In a mold-forming apparatus substantially as described, the combination of a mold box for containing moldable material and removable means forming a passage in said material, compression means comprising a pressure head and an expandible diaphragm defining therewith a fluid-tight chamber and engaging in pressing relation on said material, a tubular guide on said head substantially aligned with said passage-forming means and open to the chamber, a substantially rigid bulb on the diaphragm exteriorly of the chamber substantially in alignment with said passage-forming means and engaging therewith in reservoir-forming relation upon expansion of the diaphragm, and a guide rod fixed to said bulb extending interiorly of the chamber engaging in said tubular guide for substantially rectilinear movement.

9. In a mold-forming apparatus substantially as described, a mold box for containing moldable material and removable means forming a passage in said material, compression means comprising a pressure head and an expandible diaphragm defining therewith a fluid-tight chamber and exerting compressional forces on the moldable material, a substantially rigid projection on said diaphragm exteriorly of said chamber substantially aligned with said passage-forming means and engaging therewith upon expansion of the diaphragm to form a reservoir in the material, a guide member extending interiorly of the chamber secured to said projection, and a substantially straight tubular formation on said head guidingly receiving said member for substantially rectilinear reciprocation thereof.

10. In a mold-forming apparatus substantially as described, a mold box for containing moldable material and means defining a passage in said material, compression means engaging said mold box comprising a pressure head and an expandible diaphragm defining therewith a fluid-tight chamber and exerting compressional forces on said moldable material, a projection on said diaphragm exteriorly of said chamber engaging said passage-defining means to form a reservoir upon expansion of the diaphragm, a guide member extending interiorly of the chamber from said projection, and guide means fixed in the chamber reciprocably receiving said member and controlling therewith movement of the projection into engagement with said passage-forming means.

11. In a mold-forming apparatus substantially as described, a mold box for containing moldable material, compression means engaging said mold box including a pressure head and a diaphragm defining therewith a fluid-tight expandible chamber and exerting compressional forces on said moldable material, a projection on said diaphragm exteriorly of said chamber forming a recess in said material, a guide member extending interiorly of the chamber from said projection, and means fixed in the chamber guidingly receiving said member for substantially rectilinear reciprocation thereof.

12. In a mold-forming apparatus substantially as described, a mold box containing moldable material, compression means comprising a pressure head and an expandible diaphragm defining therewith a fluid-tight chamber and exerting compressional forces on said moldable material, a projection on the diaphragm exteriorly of the chamber movable by the diaphragm forming a depression in said material, a guide member secured to said projection extending interiorly of the chamber, and guide means fixed in the chamber guidingly receiving said member for reciprocable movement determining the path of said projection.

13. As an article of manufacture, a diaphragm construction comprising a sheet of elastic material, a substantially rigid bulb formed on said sheet and projecting from one face thereof, and a guide member fixed to the bulb projecting from the opposite face.

14. A diaphragm construction for use in mold-forming apparatus of the type described, comprising an expandible web having a substantially rigid bulb thereon and project-

ing from one face thereof and a guide member fixed to
said bulb extending from the opposite face.
